ABSTRACT

Pharmaceutical preparations containing a combination of the antihypertensively active amino acid and of a β -hydroxylase inhibitor for the treatment of hypertension. Said preparations prolong the antihypertensive action substantially greater than that would be achieved by administration of individual compounds.

10 Claims, No Drawings

PHARMACEUTICAL PREPARATIONS FOR THE
TREATMENT OF HYPERTONIA

The invention relates to new pharmaceutical preparations for the treatment of hypertension. These new pharmaceutical preparations contain a combination of an anti-hypertensively active aminoacid and a β -hydroxylase inhibitor.

Anti-hypertensively active aminoacids are above all compounds of the type of α -methyldopa.

Anti-hypertensively active aminoacids, above all compounds of the type of α -methyldopa, especially α -methyldopa itself, have proved successful in the therapy of hypertension. Thus, α -methyldopa is used successfully in practically all forms of hypertension, at a dosage of about 0.5 g to about 2 g, and at times even up to about 4 g, per day, compare E. Mutschler, *Arzneimittelwirkungen (Effects of Medicines)*, Wissenschaftliche Verlagsgesellschaft, mbH, Stuttgart 1970, page 134.

β -Hydroxylase inhibitors, for example bis-(diethylthiocarbamoyl)-disulphide, bis-[(3-aza-3-methyl-hexylene-1,6)-thiocarbamoyl]-disulphide and above all compounds of the type of fusaric acid, especially fusaric acid and its salts, such as its calcium salt, have also proved very successful in the therapy of hypertension, compare Jap. Circ. J. 35, 339 (1971).

It has now been found, surprisingly that by treatment of hypertension with a combination of an anti-hypertensively active aminoacid and a β -hydroxylase inhibitor the antihypertensive action can be prolonged and be rendered more even and the dosage of the components, that is to say of the antihypertensively active aminoacid and of the β -hydroxylase inhibitor, can be reduced, as can be shown by Goldblatt's method on male, renal hypertonic rats on administration of customary doses of the components orally or subcutaneously. The prolongation of the anti-hypertensive action here proves to be substantially greater than would correspond to the sum of the anti-hypertensive action of the active substance components.

This prolongation of the anti-hypertensive action makes it possible to manage with a single daily administration of the combination preparation according to the invention. The substantially more even action in lowering the blood pressure considerably reduces the disadvantages of a fluctuation in blood pressure in the course of the day, such as occurs in the known treatment of hypertension by means of the individual active substance components, and makes the therapy more balanced and more easily tolerated from the point of view of the patients. The reduction in the component dosages reduces the dangers of an overdosage and is of advantage especially because of the known high doses of the anti-hypertensively active aminoacids, especially of the compounds of the type of α -methyldopa, so that a general reduction in the strain on the organism of the patient is achievable.

Possible compounds of the type of α -methyldopa are above all α -amino- α -methyl- β -hydroxyphenyl-propionic acids, their salts and esters.

Salts are especially salts with bases, such as alkali metal carbonates, for example sodium carbonate or potassium carbonate, alkali metal bicarbonates, alkali metal hydroxides, such as sodium hydroxide or potassium hydroxide, or corresponding alkaline earth metal compounds, such as those of calcium or magnesium, or

ammonia, as well as amines, such as aliphatic amines, for example lower alkylamines, such as trimethylamine or triethylamine, and also aluminium compounds, such as aluminium hydroxide, for example salts of two mols of acid and one mol of aluminium hydroxide which are suitable especially because of their slower resorption, lack of odour and low gastro-intestinal disturbances.

Esters are above all lower alkyl esters, such as methyl esters and ethyl esters. Lower radicals are, in the preceding and following texts, above all those with up to 7, preferably with up to 4, C atoms.

Compounds to be singled out particularly are α -amino- α -methyl- β -(4-hydroxyphenyl)-propionic acid and very particularly α -amino- α -methyl- β -(3,4-dihydroxyphenyl)-propionic acid, which is known by the name of α -methyldopa, as well as their salts, such as, in particular, their alkali metal salts or alkaline earth metal salts, and secondly their esters, such as lower alkyl esters.

β -Hydroxylase inhibitors are, for example, bis-(diethylthiocarbamoyl)-disulphide, bis-[(3-aza-3-methyl-hexylene-1,6)-thiocarbamoyl]-disulphide and especially compounds of the type of fusaric acid.

Possible compounds of the type of fusaric acid are above all those of the formula I

wherein R₁ is an esterified or amidised carboxyl group but above all a free carboxyl group and R₂ is an alkyl group, and their salts.

An esterified carboxyl group is, for example, a carboxyl group which is esterified with a lower alkanol, with the lower alkanol in particular having up to 8, preferably up to 4, C atoms and being branched, or preferably, straight-chain in the alkyl part. As examples of an esterified carboxyl group there may be mentioned: n-butoxycarbonyl, n-propoxycarbonyl, i-propoxycarbonyl and in particular ethoxycarbonyl and very especially methoxycarbonyl.

An amidised carboxyl group is, for example, a N-monosubstituted or N-disubstituted carbamoyl group and very particularly the N-unsubstituted carbamoyl group. As substituents there may be mentioned: lower alkyl, especially with up to 8 C atoms, such as branched or, in particular, straight-chain lower alkyl with, in particular, up to 4 C atoms, for example n-butyl, n-propyl, i-propyl and especially ethyl and very particularly methyl.

An alkyl group R₂ is, in particular, a branched or above all a straight-chain alkyl group with up to 9 C atoms, preferably n-pentyl and very particularly n-butyl.

Salts are especially salts with bases, such as those mentioned above, above all alkali metal salts and alkaline earth metal salts, and very particularly the calcium salt.

Depending on the number of their asymmetric carbon atoms the active substances mentioned can be present in the form of isomer mixtures, pure isomers (racemates) or optical antipodes. Preferably they are in each case used in the form of the more active or less toxic isomer or antipode. For example, as α -methyldopa its laevo-rotatory antipode can preferably be used.

Active substances with basic groups, especially esters of the type of α -methyldopa, can be present in the free form or in the form of their non-toxic salts. Possible salts of this nature are especially salts with organic or inorganic acids, such as hydrogen halide acids, sulphuric acid, phosphoric acid, nitric acid, perchloric acid, aliphatic, alicyclic, aromatic or heterocyclic carboxylic acids or sulphonic acids, such as formic, acetic, propionic, succinic, glycollic, lactic, malic, tartaric, citric, ascorbic, maleic, hydroxymaleic or pyruvic acid; phenylacetic, benzoic, p-aminobenzoic, anthranilic, p-hydroxybenzoic, salicylic or p-aminosalicylic acid, embolic acid, methanesulphonic, ethanesulphonic, hydroxyethanesulphonic and ethylenesulphonic acid; halogenobenzenesulphonic, toluenesulphonic and naphthalenesulphonic acid or sulphanilic acid; cyclohexyl-sulphamic acid, methionine, tryptophane, lysine or arginine.

The invention relates both to pharmaceutical preparations containing a combination of an anti-hypertensively active aminoacid, especially one mentioned above as being preferred, and a β -hydroxylase inhibitor, especially one mentioned above as being preferred, and to the manufacture of such preparations as well as the use of the active compounds in the form of the said preparations, or by combined but separate administration, for the treatment of hypertension.

Pharmaceutical preparations to be particularly singled out contain, as the anti-hypertensively active aminoacid, α -amino- α -methyl- β -(4-hydroxyphenyl)-propionic acid or α -amino- α -methyl- β -(3,4-dihydroxyphenyl)-propionic acid or a salt or a lower alkyl ester thereof, and as the β -hydroxylase inhibitor, a compound of the formula II

wherein R_1' is lower alkoxy carbonyl, carbamoyl or carboxyl and R_2' is alkyl with 3-6 C atoms, or a salt thereof.

Suitable preparations are, in particular, also those which contain, as the anti-hypertensively active aminoacid, α -methyl-p-tyrosine or a salt thereof, and, as the β -hydroxylase inhibitor, a compound of the formula II

wherein R_1' is lower alkoxy carbonyl, carbamoyl or carboxyl and R_2' is alkyl with 3-6 C atoms, or a salt thereof, or bis-(diethylthiocarbamoyl)-disulphide or bis-[(3-aza-3-methylhexylene-1,6)-thiocarbamoyl]-disulphide. Other suitable preparations are in particular also those which contain, as the anti-hypertensively active aminoacid, α -amino- α -methyl- β -(4-hydroxyphenyl)-propionic acid or α -amino- α -methyl- β -(3,4-dihydroxyphenyl)-propionic acid or a salt or a lower alkyl ester thereof and, as the β -hydroxylase inhibitor, bis-(diethylthiocarbamoyl)-disulphide or bis-[(3-aza-3-methylhexylene-1,6)-thiocarbamoyl]-disulphide.

Very particularly preferred pharmaceutical preparations are those which contain, as the anti-hypertensively active aminoacid, α -amino- α -methyl- β -(3,4-dihydroxyphenyl)-propionic acid (α -methyldopa), or the methyl ester, ethyl ester or a salt thereof, or α -methyl-p-tyrosine, and, as the β -hydroxylase inhibitor, 5-n-pentyl-picolinic acid or preferably 5-n-butylpicolinic acid (fusaric acid), or the methyl ester, ethyl ester or a salt thereof, or bis-(diethylthiocarbamoyl)-disulphide or bis-[(3-aza-3-methylhexylene-1,6)-thiocarbamoyl]-disulphide.

The invention above all, however, relates to pharmaceutical preparations containing α -amino- α -methyl- β -(3,4-dihydroxyphenyl)-propionic acid or a non-toxic salt thereof and 5-n-butyl-picolinic acid or a non-toxic salt thereof.

Accordingly, the use of these preferred preparations or the use of the individual components in a combination therapy is also a particular subject of the invention.

In the new preparations, the ratio of the antihypertensively active aminoacid to the β -hydroxylase inhibitor can vary within considerable limits.

The dosage of the new preparations depends on the effectiveness of the active substance components concerned and on the individual requirements of the patient. Using the preparations according to the invention the daily dosage of the active substance components can generally be reduced to between about half and one-third of the customary separate daily dosage.

Thus, for example, the abovementioned preparations which have particularly been singled out can contain about 100-200 mg, especially 150-200 mg, of α -amino- α -methyl- β -(3,4-dihydroxyphenyl)-propionic acid and about 50-200 mg, especially 100-200 mg, of the calcium salt of 5-n-butylpicolinic acid.

The preferred preparations can, however, also contain about 100-200 mg, especially 150-200 mg, of α -amino- α -methyl- β -(3,4-dihydroxyphenyl)-propionic acid and about 40-150 mg, especially 60-100 mg, of bis-(diethylthiocarbamoyl)-disulphide or bis-[(3-aza-3-methylhexylene-1,6)-thiocarbamoyl]-disulphide.

The daily dosage is about 1-6 such individual doses, which are preferably administered all at once.

The pharmaceutical preparations according to the invention are principally suited to oral or parenteral administration and are preferably in the form of a mixture with a pharmaceutical, organic or inorganic, solid or liquid excipient which is suitable, for example, for enteral or parenteral administration. Possible substances for forming the excipient are those which do not react with the active substances such as, for example, water, gelatine, lactose, starch, stearyl alcohol, magnesium stearate, talc, vegetable oils, benzyl alcohols, gum, propylene glycols, white petroleum jelly or other known medicinal excipients. The pharmaceutical preparations can, for example, be in the form of tablets, dragees, capsules or suppositories or in a liquid form as solutions (for example as an elixir or syrup), suspensions or emulsions. They are optionally sterilised and/or contain auxiliaries such as preservatives, stabilisers, wetting agents or emulsifiers, solubilising agents or salts for regulating the osmotic pressure or buffers. They can also contain other therapeutically valuable substances.

The pharmaceutical preparations are formulated in accordance with customary methods.

The anti-hypertensively active aminoacids employed, and the β -hydroxylase inhibitors, are known.

The invention is explained with the aid of the examples which follow without thereby in any way intending to restrict the scope of the invention.

EXAMPLE 1

Tablets containing 200 mg of α -methyldopa and 300 mg of the calcium salt of fusaric acid:

Composition	
α -Methyldopa	200 mg
Calcium salt of fusaric acid	300 mg
Lactose	41 mg
Wheat starch	75 mg
Colloidal silica	16 mg
Talc	16 mg
Magnesium stearate	2 mg
	650 mg

Manufacture

The α -methyldopa and the calcium salt of fusaric acid are mixed with the lactose, a part of the wheat starch and with colloidal silica and the mixture is forced through a sieve. A further part of the wheat starch is worked into a paste with a 5-fold amount of water on a water bath and the powder mixture is kneaded with this paste until a slightly plastic mass has been produced.

The plastic mass is forced through a sieve of approx. 3 mm mesh width and dried and the dry granules are again forced through a sieve. Thereafter the residual wheat starch, talc and magnesium stearate are mixed in and the resulting mixture is pressed to give tablets weighing 650 mg (having a breaking groove).

EXAMPLE 2

Tablets containing the following active substances are manufactured analogously to Example 1:

α -Methyldopa	200 mg
Bis-(diethylthiocarbamoyl)-disulphide	80 mg

EXAMPLE 3

Tablets containing the following active substances are manufactured analogously to Example 1:

α -Methyldopa	200 mg
Bis-[3-aza-3-methyl-hexylene-1,6]-thiocarbamoyl]-disulphide	80 mg

I claim:

1. A pharmaceutical preparation for treating hypertension which contains an effective amount of an antihypertensive amino acid compound selected from the group consisting of an α -amino- α -methyl- β -(hydroxylated phenyl)-propionic acid, a non-toxic salt thereof and a lower alkyl ester thereof; and an effective amount of a β -hydroxylase inhibitor compound selected from the group consisting of a compound of the formula

5 wherein R₁ is an esterified, amidised or free carboxyl group and R₂ is an alkyl group, a non-toxic salt thereof, bis-(diethylthiocarbamoyl)-disulphide and bis-[3-aza-3-methylhexylene-1,6]-thiocarbamoyl]-disulphide.

2. The pharmaceutical preparation of claim 1, containing an effective amount of a compound selected from the group consisting of α -amino- α -methyl- β -(4-hydroxyphenyl)-propionic acid, α -amino- α -methyl- β -(3,4-dihydroxyphenyl)-propionic acid and nontoxic salts thereof and an effective amount of a β -hydroxylase inhibitor selected from the group consisting of fusaric acid, bis-(diethylthiocarbamoyl)-disulphide and bis-[3-aza-3-methyl-hexylene-1,6]-thiocarbamoyl]-disulphide.

3. The pharmaceutical preparation of claim 1, which contains an effective amount of a compound selected from the group consisting of α -amino- α -methyl- β -(4-hydroxyphenyl)-propionic acid, α -amino- α -methyl- β -(3,4-dihydroxyphenyl)-propionic acid, the alkali metal salts and alkaline earth metal salt thereof and an effective amount of a compound selected from the group consisting of 5-n-pentyl-picolinic acid, 5-n-butyl-picolinic acid, methyl and ethyl esters thereof and nontoxic salt thereof.

4. The pharmaceutical preparation of claim 1, which contains an effective amount of a compound selected from the group consisting of α -amino- α -methyl- β -(3,4-dihydroxyphenyl)-propionic acid, non-toxic alkali metal salts thereof and non-toxic alkaline earth metal salts thereof and an effective amount of a compound selected from the group consisting of 5-n-butyl-picolinic acid, its methyl or ethyl ester, and a non-toxic salt thereof.

5. The pharmaceutical preparation of claim 1, which contains α -amino- α -methyl- β -(3,4-dihydroxyphenyl)-propionic acid or a non-toxic salt thereof and 5-n-butyl-picolinic acid or a nontoxic salt thereof.

6. The pharmaceutical preparation of claim 1, which contains effective amounts of α -amino- α -methyl- β -(3,4-dihydroxyphenyl)-propionic acid or a non-toxic salt thereof, and bis-(diethylthiocarbamoyl)-disulphide.

7. The pharmaceutical preparation of claim 1, which contains effective amounts of α -amino- α -methyl- β -(3,4-dihydroxyphenyl)-propionic acid or a non-toxic salt thereof, and bis-[3-aza-3-methyl-hexylene-1,6]-thiocarbamoyl]-disulphide.

8. The pharmaceutical preparation of claim 1, containing 100-200 mg of α -amino- α -methyl- β -(3,4-dihydroxyphenyl)-propionic acid and 50-200 mg of the calcium salt of 5-n-butylpicolinic acid.

9. The pharmaceutical preparation of claim 1, containing 150-200 mg of α -amino- α -methyl- β -(3,4-dihydroxyphenyl)-propionic acid and 100-200 mg of the calcium salt of 5-n-butylpicolinic acid.

10. Process for the treatment of hypertension, characterized in that a pharmaceutical preparation of claim 1 is administered to a warm-blooded organism.
